is Attorney
Mitchell & Allen.

UNITED STATES PATENT OFFICE.

ALEXANDER K. SUTHERLAND, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

STARTING-SWITCH.

1,229,670.

Specification of Letters Patent. Patented June 12, 1917.

Application filed May 11, 1916. Serial No. 96,805.

To all whom it may concern:

Be it known that I, ALEXANDER K. SUTHERLAND, a citizen of the Dominion of Canada and subject of King George V, residing at New Britain, Connecticut, have invented a new and useful Starting-Switch, of which the following is a specification.

My invention relates particularly to what is commonly known as a star-delta motor starting switch, and the main object is to provide a simple and reliable construction in which the operator can first close the switch in the proper starting relation only and subsequently move it to the proper running position.

Another object is to provide such a construction with an automatic catch to hold the switch in the running position.

Another object is to automatically release such a construction upon overload.

Figure 1 is a plan view of the switch embodying the improvements of my invention, parts being shown in the running position, and the casing being partially sectioned and broken away.

Fig. 2 is a fragmentary side view showing the operating handle and detents. The operating handle is shown in full lines in the running position, and in dotted lines in the open circuit position, and also in dotted lines in the starting position.

Fig. 3 is a side view of the switch contacts in the running position but showing also in dotted lines the movable parts of the switch in the open circuit position and also in the starting position.

Fig. 4 is a fragmentary enlarged sectional view of the handle detents taken on the plane of the line 4—4 of Fig. 2.

Fig. 5 is a diagrammatic view showing the switch parts and circuits in the starting position.

Fig. 6 is a similar view showing the parts and circuits in the running position.

An insulating base 10 is provided as is customary in such constructions and upon it are mounted three hinged blades 11, 12 and 13. In line with these blades are mounted respectively the contact jaws 11^a, 11^b, 12^a, 12^b, 13^a and 13^b. The three main wires are connected to the switch blades 11, 12 and 13. The motor coils or groups X, Y and Z are connected as shown in Figs. 5 and 6, the ends 1, 2, of coil X being connected to contacts 11^a and 12^b, the ends 3, 4, of coil Y being connected to contacts 12^a and 13^b, and the ends 5, 6, of coil Z being connected to contacts 13^a and 11^b.

The blades 11, 12 and 13 all pass through an insulating block 14 which is located between the inner and outer contacts. This block 14 at its lower edge also carries three stub-like short circuiting blades 15, 16 and 17, which are adapted to engage respectively the contacts 11^b, 12^b and 13^b when the parts are in the starting position. The insulating guard 18 is preferably located at the inner face of each of the outer contacts 11^b, 12^b and 13^b, and each of these contacts has an over-hanging part 19. The contacts 11^a, 12^a and 13^a are all considerably higher than the contacts 11^b, 12^b and 13^b, so that when the switch is first closed, the blades 11, 12 and 13 engage the contacts 11^a, 12^a and 13^a just before the blades 15, 16 and 17 engage the contacts 11^b, 12^b and 13^b.

When the switch is in the position shown in Fig. 5, the coils of the motor are all connected together in what is known as the "star" relation, and when the parts are moved into the position shown in Fig. 6, the motor coils are in what is known as the "delta" relation.

An inclosure 20 and cover 21 may be provided. In the form shown, an arm 22 is secured to the upper edge of the insulating block 14 and secured to the rock shaft 23 which projects through one side of the casing. An external handle 24 is provided for this shaft for operating the switch in one direction and a spring 25 is provided for opening the switch. It will be noted that the parts are so related to each other that the switch can only be started in the proper motor starting position. I have also provided means which makes it necessary for the operator to hold the switch at least momentarily in the motor starting position, and thus serve as a warning as to the proper operation of the switch. The operating handle 24 is provided at its rear face with a flat spring 26. The member 27 is secured to the outside of the box or casing and constructed to coöperate with the spring 26. This member is provided with an incline portion 28 and a shoulder 29 in such a posi-

tion relative to the incline that as the switch handle is moved downward the blade 26 rides up the incline 28 and then snaps into position shown in section in Fig. 4 where 5 the spring 26 engages the shoulder 29. In this position the shoulder 30 prevents the further downward movement of the spring 26 and the operating handle. It will thus be seen that it is necessary to let up on the 10 operating handle sufficiently to permit the spring 26 to snap over the shoulder 29 into the position shown in dotted lines, in Fig. 4. The operating handle may then be moved downward into the running position.

15 Preferably, a spring pressed catch 31 is provided for holding the operating handle in the running position, as shown in Figs. 1 and 2. I also preferably provide an automatic release for this catch. This release 20 consists of a coil 32 which is connected to the switch contacts 12^a and 13^a and provided with a plunger or armature 33 which is adapted to release the catch 31 from the operating handle and permit the spring 25 25 to retract the switch blades and open the circuit. Preferably, a yielding stop 34 is provided for the handle on its return movement.

What I claim is:

30 1. In a switch of the character described, the combination of three movable main switch blades, a series of switch contacts adapted to be engaged by said blades in the initial movement thereof, a second series of 35 contacts having contact surfaces adapted to be engaged by said blades in a later movement thereof and a series of short circuiting blades movable in the same planes with the main blades respectively and disposed to 40 engage said same contact surfaces of the second series of contacts and to connect said series of contacts prior to engagement by said main blades.

2. In a switch of the character described, 45 the combination with relatively stationary and movable members, of a spring carried by one of said members and an inclined abutment on the other of said members for engagement by said spring in the relative

50 movement of the two members toward each other, a stop shoulder for the spring located in advance of the spring supporting surface of the abutment, a shoulder at one edge of said stop shoulder to limit the lateral movement of the spring on said stop shoulder, said limiting shoulder being laterally offset from the supporting surface of the abutment to enable the spring when engaging the stop shoulder to move laterally far enough 55 60 to clear the supporting surface of the abutment and said limiting shoulder further being of a height such that upon a limited reverse movement of the members the spring will be free of the limiting stop and will 65 exert its tension to clear said stops and there-

by enable a continuance of the movement first initiated.

3. In a switch of the character described, a hinged blade, a stationary contact having a lateral extension for engagement by said hinged blade, a supplementary blade movable with the hinged blade and disposed in the same plane therewith to engage and pass beyond the lateral extension prior to the engagement of said lateral extension by the hinged blade and a relatively stationary insulating guard interposed between the stationary contact and the supplementary blade when the hinged blade is in engagement with the lateral extension of the switch contact. 70 75 80

4. In a switch of the character described, a hinged blade, a stationary contact, an insulating member carried by said blade, a shorter blade carried by said insulating member beneath and in the same plane as said first blade, said contact having a lateral extension at its upper end adapted to be engaged successively by said blades, and an insulating guard secured along the face of said contact beneath said extension. 85 90

5. In a starting switch, the combination of two sets of stationary contacts and two sets of movable contacts, one set of movable contacts being insulated from the other set of movable contacts, one set of stationary contacts being disposed to be engaged successively by both sets of movable contacts, a casing inclosing said stationary and movable contacts, operating means extending through the wall of the casing and mechanically connected with the movable contacts and an automatic stop comprising a member carried by the switch operating means and a member supported on the wall of the casing arranged to be engaged by the member 95 100 on the operating means to stop the movement of said operating means but arranged to release said operating means upon a slight backward movement of said operating means. 105 110

6. In a switch of the character described, a movable switch member, an operating handle therefor, a spring member movable with said operating handle, means for engaging said spring to automatically stop 115 the movement of said handle in one direction, means for releasing said spring and means for automatically catching said operating handle.

7. In a switch of the character described, 120 a movable switch member, an operating handle therefor, a spring member movable with said operating handle, a set of contacts engageable by said switch member, means for engaging said spring to automatically stop the movement of said handle when said switch member has been engaged with said contacts and adapted after such engagement to release said spring member, a second set of contacts engageable by the 125 130

switch member in the further movement of the switch member by the handle, means for automatically catching said operating handle when the switch member has been engaged 5 with said second set of contacts and means for automatically releasing said catching means.

8. In a switch of the character described, the combination of three main hinged blades, 10 a second set of three blades insulated from the first, but movable in the same plane therewith and electrically connected together, a set of contacts arranged to be engaged by the main blades and a second set 15 of contacts arranged to be engaged successively by both sets of blades.

9. In a switch of the character described, the combination of three main hinged blades, a second set of three blades insulated from 20 the first, but movable in the same planes respectively therewith and electrically connected together, a set of contacts arranged to be engaged by the main blades and a second set of contacts arranged to be engaged successively by both sets of blades, and means for automatically stopping the movement of said blades when the blades of 25 said second set of blades are in engagement with their respective contacts.

30 10. In a starting switch, the combination of two sets of stationary contacts and two sets of movable contacts, one set of movable contacts being insulated from the other set of movable contacts, one set of stationary contacts being arranged to be engaged by one set of movable contacts and the other set of stationary contacts being arranged to be engaged successively by both sets of contacts, an inclosure 35 for all of said stationary and movable contacts, an operating handle outside of said inclosure mechanically connected to said movable contacts for operating the same, and an automatic stop on the outside of said inclosure comprising stationary and movable parts arranged to stop the movement of the operating handle and the movable contacts in one position but arranged to become disengaged upon a slight backward movement 40 45 50 of said operating handle, and arranged when thus disengaged to permit the completion of

the movement of the operating handle and the movable contacts.

11. In a starting switch, the combination of two sets of stationary contacts and two sets of movable contacts, one set of movable contacts being insulated from the other set of movable contacts, one set of stationary contacts being arranged to be engaged by one set of movable contacts and the other set of stationary contacts being arranged to be engaged successively by both sets of contacts, an operating handle mechanically connected to said movable contacts for operating the same, and an automatic stop comprising stationary and movable parts arranged to stop the movement of the operating handle and the movable contacts in one position but arranged to become disengaged upon a slight backward movement of said operating handle, and arranged when thus disengaged to permit the completion of the movement of the operating handle and the movable contacts, means for automatically returning the operating handle and movable contacts from any position to open circuit position when the operating handle is released. 60 65 70 75

12. In a starting switch, the combination of a plurality of hinged blades, a plurality of stationary contacts adapted to be engaged by each blade respectively, means for connecting motor coils in one relation when the blades are connected with one set of contacts, means for connecting said motor coils 80 85 in another arrangement when said blades are in contact with the other set of contacts, an inclosure for said contacts and said blades, a handle on the outside of said inclosure for operating said blades, means for stopping the closing action of said blades when said blades are in connection with said first mentioned set of contacts, said means being adapted to be released when said handle is slightly retracted to permit said handle and said blades to be operated subsequently for connecting said blades with said second mentioned set of contacts, said stopping means being located exteriorly to 90 95 said inclosure.

ALEXANDER K. SUTHERLAND.
